REVOLVING DOOR

Frederick William Johnson, Brighton, England

Application June 30, 1932, Serial No. 620,131, and
in Great Britain July 13, 1931

4 Claims. (Cl. 20—18)

My present invention relates to revolving doors, and has for its object to provide an improved construction of a device for use in conjunction with revolving doors for automatically returning the door to a predetermined normal position. In such devices it has been proposed heretofore to provide tension springs which are stretched as the door is opened so that they reassert themselves and close the door when the door is released.

According to this invention a device for the purpose set forth comprises a member with a cam shaped or elliptical track and a loaded member engaging its said track one of said members moving with the door, the arrangement being that said loaded member is displaced against the influence of its load as the door is rotated by reason of the engagement with said cam shaped or elliptical track so as to store up energy which upon release of the door returns the door to the predetermined normal position.

The preferred form of my invention briefly consists in the provision of a cam like track with which is engaged a member translatable moved over the said track when the door is rotated, the arrangement being that the said member is displaced by reason of its engagement with the cam shaped track and mechanically applies a load to spring means so as to store up energy therein which upon release of the door sets into operation means for returning the door to a predetermined normal position.

Briefly an embodiment of my invention comprises a pivot to which the door is attached, the said pivot having secured to it for rotation there-with a plate or frame carrying a pair of torsion springs, the said plate or frame having fitted thereto a pair of arms having free ends formed with runners engaging a continuous cam shaped or elliptical track disposed about the said plate or frame and spaced therefrom, the said arms carrying lateral toothed segments or rack bars travelling over gear wheels rotatable on spindles coaxial with said torsion springs and adapted to twist the torsion springs to store up energy therein when the door is rotated by reason of the movement of said arms about their pivots consequent upon their runners travelling over the said cam shaped or eccentric track.

In order that my invention may be clearly understood and readily carried into effect, I have appended hereto a drawing illustrating an embodiment thereof and wherein,

Fig. 1 is a sectional side elevation view showing an embodiment of my invention as applied

to the upper end of a door. It will be understood that by reversal of this device it can also be fitted to the lower end of the door.

Fig. 2 is a plan view of Fig. 1.

Fig. 3 is a detail sectional side elevation view showing a suitable method of supporting the toothed segments which operate the torsion springs hereinbefore referred to.

Referring to the drawing, the spindle to which the centre of the upper horizontal edge of the door is affixed is indicated by the reference numeral 1 and it rotates within a casing 2 which is recessed in the ceiling or super structure of the door. Fixed to the spindle 1 for example by being engaged over a square extremity 3 is a plate 4 which can conveniently be a disc as shown in Fig. 2. The periphery of this disc is spaced from a plate 5 which is formed with an elliptical inner edge 6. The location of the disc 4 within the plate 5 is such as to provide a symmetrical space between them as more clearly shown in Fig. 2. The plate 5 can be secured within the casing 2 by means of screws 7 which pass through the plate 5 and diagonal supports 8 in the corners of the casing 2. The eccentric inner edge 6 of the plate 5 constitutes a cam track which when the disc or plate 4 is rotated with the door imparts pivotal oscillation to a pair of arms 9 each pivoted at one end by a bolt 10 to the member 4 contiguous to the periphery 85 of the member 4, the other ends of the arms 9 being free and carrying rollers 11 the peripheries of which are grooved so that they run over the elliptical edge 6, the said edge preferably being rounded as shown in Fig. 1. The rollers 11 are 90 located upon diametrical opposite sides of the member 4 and are constantly in contact with the edge 6 of the plate 5. Normally the position occupied by the plate 4 and rollers 11 is that indicated in Fig. 2 in which the rollers 11 contact with the opposite points of the edge 6 containing the largest diameter of the ellipse. This normal location is automatically obtained by the influence of coiled torsion springs 12 accommodated in sleeves 13 each abutting at one end 100 against a collar 14 and at the other end against a bevel pinion 15. Each collar 14 receives one end of the appropriate coiled torsion spring 12 and is rotatably disposed about a pin 16 and is locked in selected position by passing a pin 105 through one of a number of radial holes 17 into the pin 16. The pin 16 is locked at its outer end in a boss 18 by passing a pin through a hole 19 in such boss into one or a number of holes 20 in the pin 16. Each boss 18 comprises part 110

of a bracket or plate 21 secured by screws 22 to the member 4.

The ends of the coiled torsion springs remote from the collars 14 are each secured to the appropriate pinion 15, each said pinion being fixed on a spindle 23 rotated in a boss 24 of a bracket 25 secured by screws 26 to the member 4.

The pinions 15 are rotated so as to apply a torsional load to the springs 12 by reason of the arms 9 being swung inwards as their rollers 11 travel around the track 6 and this is effected by pivotally connecting to the free end of each arm 9 an arcuate toothed rack or segment 27, the pivotal connection being indicated at 28. Each toothed rack 27 is preferably guided between the appropriate pinions 15 and one or more rollers 29 supported in bearing members 30 secured to the member 4 as shown in Fig. 3.

It is preferred that the plate or bracket 4 shall be provided with an anti-friction guide to assist its easy rotation and for this purpose it can be formed with a depending annular cage carrying balls or rollers rotating in an annular channelled guide fixed to the casing 2. However any other suitable anti-friction device may be provided for this purpose. For example for this purpose I have shown a number of rollers 31 rotating in bifurcated brackets 32 secured to the casing 2, the peripheries of these rollers contacting with the member 4.

It will be appreciated from the foregoing that the influence of the springs 12 is such as to urge the arms 9 outwards so that the rollers 11 are pressed against the cam track 6 whereby the member 4 is carried to the position shown in Fig. 2 which for normal purposes can represent that appropriate to the closed position of the door. When the door is swung open the arms 9 are necessarily forced inwards and the pinions 15 rotated so as to increase the torsion of the springs 12 with the result that if the door is freed in the open position the springs 12 will reassert themselves and close the door. An important feature of my invention consists in the fact that the door may be rotated a number of times in continuous succession without affecting the function of the spring mechanism for closing the door. The mechanism above proposed will produce an easy running action which can be accommodated in a small space and in which the spring means can be readily adjusted by means of the collars 14 and pins 16.

What I claim is:—

1. A device for use in conjunction with revolving doors for automatically returning a revolving door to a predetermined normal position comprising a member with a cam shaped track and a loaded member engaging its said track, one of said members being connected with the door and the other being separate from the door so that the one connected with the door is carried along the other as the door is moved to the open position, the arrangement being such that said loaded

member is gradually displaced against the influence of its load as the door is rotated by reason of its engagement with and the shape of the said cam shaped track so as to store up energy which upon release of the door returns the door to the closed position.

2. A device for use in conjunction with revolving doors for automatically returning a revolving door to a predetermined normal position consisting of a cam like track, a spring for returning the door to its predetermined normal position and a member engaging the cam like track and adapted to set the spring to an operative condition, said member being engaged with and translatable moved over the said track when the door is being rotated in the opening direction, the arrangement being such that the said member is gradually displaced as the door is being opened by reason of its engagement with the cam shaped track and mechanically applies a load to said spring so as to store up energy therein which upon release of the door sets into operation means for returning the door to the closed position.

3. A device for use in conjunction with revolving doors for automatically returning a revolving door to a predetermined normal position comprising a pivot to which the door is attached, a plate secured to the said pivot for rotation therewith, a pair of torsion springs carried by said plate, a pair of arms fitted to said plate, runners at the free ends of said arms, a continuous substantially elliptical track disposed about the said plate and spaced therefrom and engaged by said runners, lateral toothed segments carried by said arms and travelling over gear wheels rotatable on spindles coaxial with said torsion springs and adapted to twist the torsion springs to store up energy therein when the door is rotated by reason of the movement of said arms about their pivots consequent upon their runners travelling over the said cam shaped or eccentric track.

4. A device for use in conjunction with revolving doors for automatically returning a revolving door to a predetermined normal position comprising a pivot to which the door is attached, a plate secured to the said pivot for rotation therewith, a pair of torsion springs carried by said plate, a pair of arms fitted to said plate, runners at the free ends of said arms, a continuous substantially elliptical track disposed about the said plate and spaced therefrom and engaged by said runners, lateral toothed segments carried by said arms and travelling over gear wheels rotatable on spindles coaxial with said torsion springs and adapted to twist the torsion springs to store up energy therein when the door is rotated by reason of the movement of said arms about their pivots consequent upon their runners travelling over the said cam shaped or eccentric track, and means for adjusting the torsional effort of said springs.

FREDERICK WILLIAM JOHNSON.
